(57) **CLAIM**

The ornamental design for a quarterback training device as shown and described.

DESCRIPTION

FIG. 1 is a perspective view of a quarterback training device, showing the new design;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

1 Claim, 5 Drawing Sheets
